UNITED STATES PATENT OFFICE.

FREDERICK S. McCULLOUGH, OF WILKINSBURG, PENNSYLVANIA.

SPACE DISCHARGE DEVICE.

Application filed December 11, 1922. Serial No. 606,348.

This invention relates to a space discharge device, particularly a device for establishing a potential drop between points of different temperatures for effecting rectification of alternating currents.

The present invention proposes to provide a space discharge device having points between which there is a relatively great difference in temperature for producing a potential drop between such points for the purpose of rectifying alternating currents of extremely high frequency while eliminating corona and brush effects.

The invention is applicable to devices in which the power is dissipated in the device, or to a device for supplying such rectified currents to external circuits.

The invention may be understood by reference to the accompanying drawings, in 20 which:

Fig. 1 is a diagrammatic view of a space discharge device of a type in which the power is dissipated in the tube itself;

Fig. 2 is a similar view of a device wherein the rectified current is conducted to an external circuit.

In Fig. 1, 5 designates an evacuated vessel of suitable material, such as glass, around which are several turns of a conductor, forming a coil designated 6. This coil is connected with a source of high frequency alternating current, preferably a source of current alternating at radio frequency, not shown.

Within the vessel 5 is a coil 7 having the desired number of turns therein, a relatively few turns being necessary, but this is determined according to the conditions and use to which the device is put. One end of this coil is directly connected to a high resistance element 8, the opposite side of which is connected with the coil 7 in such manner that only the first few turns, designated 9, are in the closed circuit thus provided. The other end of the coil is connected with a suitable terminal 10.

When radio frequency currents are passed through coil 6, an electro-magnetic field will be produced within the tube. This will induce a current in the closed circuit including turns of wire 9 and resistance element 8, causing the latter to be heated. At each half cycle of the alternating field, terminal 10 will be positively charged and element 8 will have a negative potential, whereupon, due to the difference in temperatures, ter-

minal 10 being cold, a current will flow from the terminal 10 or anode to the resistance element 8 or cathode. When the field has reversed, and terminal 10 has a negative potential and element 8 is positive, no current will flow between these points. Rectification will thus be effected.

By reason of the coil 7 being disposed in a vacuum, currents of extremely high potential may be induced therein without interference by brush or corona discharges. Very high frequencies may thus be obtained. It will be seen that no wires enter the vessel in this construction.

Since the current changes in the coil 6 are of very great frequency, the potential difference developed between the cathode 8 and the anode 10 are very great, especially since this anode is connected to that end of the coil 7 remote from the coil 9. Electrons, therefore, hit the anode 10 with great velocity and X-rays are generated at this anode. The tube, therefore, may be employed as a source of X-rays. Since the target 10 is of apparently small area, the stream of X-rays produced is concentrated.

In the device shown in Fig. 2, the same principle, i. e., rectification across the terminals of a coil, is effected. In this figure, 12 is an evacuated vessel having a closed metallic circuit therein which includes a loop 13 and a high resistance element 14. A coil 15 is placed in the vessel around the high resistance element 14, and this coil is connected with a source of radio-frequency currents, not shown. A conductor 16 serves to connect the loop 13 with one side 17 of the line to coil 15, and an ammeter is shown in this circuit between the loop and the line. Other devices than an ammeter may, of course, be connected in this circuit.

The radio frequency currents in coil 15 serve to induce an alternating current in 13 and resistance 14, heating the latter. When element 13 has become heated to a relatively high temperature, a direct current will flow through the ammeter circuit at extremely high voltages at every positive half cycle of point A of coil 15. During the other half cycle, when point A is negative, no current will flow. Rectification is thus effected.

Because the potential is built up in a vacuum, currents of extremely high voltage may be reached without corona effects and brush-

The hot body 14 may serve as a cathode

and the loop 13, being cold, may serve as an anode so that X-rays are developed in this tube in a way similar to that explained in connection with Fig. 1. Since the rectangle 5 13 is of considerable area, the X-rays produced in this way are not confined to a small beam and the tube may be used when a distributed radiation is required. The tube shown in Fig. 2 may also be used as a rectifier, direct current being produced from 10 alternating, as already explained.

Obviously, various changes and modifications may be made in the device, it being understood that the drawings and description 15 are merely illustrative of my invention.

What I claim is:

1. A space discharge device comprising an evacuated vessel having means wholly within said envelope for building up currents of high potential from energy supplied by means outside said envelope, and means in the vessel for effecting rectification of such currents. 20
2. A space discharge device comprising an evacuated vessel, a coil through which radio frequency alternating currents may be passed, and means deriving energy from this coil for effecting rectification of the currents which are supplied to the coil. 25
3. A space discharge device comprising an evacuated vessel, a coil associated with the vessel through which high frequency currents constituting the energy to be rectified are passed, means in the vessel for rectifying alternating currents, said means deriving the energy to be rectified from said coil, said means including a hot cathode and means also deriving energy from said coil for heating the cathode. 30
4. A space discharge device comprising an evacuated vessel, a coil in the vessel, and means for establishing a temperature difference between opposite ends of the coil to enable a space current to flow from the cold 40 to the hot ends when the cold end has a positive potential, whereby rectification of alternating currents may be effected. 45
5. A space discharge device comprising an evacuated vessel, a coil associated with the vessel adapted to receive energy alternating at high frequencies, a cathode in the vessel comprising a high resistance element in a closed circuit, which circuit derives energy for heating the cathode from high frequency alternating currents in the coil by inductance, and a circuit including the cathode for receiving and rectifying energy from the coil. 55
6. A space discharge device comprising an

evacuated vessel, a coil for connection in 60 a radio frequency current associated with the vessel, a coil within the vessel in transformer relation to said first named coil, a hot cathode connected with one end of the last named coil, an anode connected with 65 the other end of the coil.

7. A space discharge device comprising an evacuated vessel, a coil for connection in a high frequency current surrounding the vessel, a second coil within the vessel in inductive relation to the first coil, a cathode connected to one end of the coil, an anode at the other end of the coil, and means for heating the cathode, whereby a current may flow in one direction between the anode and 70 cathode when the latter is heated, said device enabling a high frequency current to be built up and dissipated in the vessel 75 without brushing or corona effects.

8. A space discharge device comprising an evacuated vessel, a coil for connection in a high frequency current surrounding the vessel, a second coil within the vessel in inductive relation to the first coil, a cathode at one end of the coil, an anode connected to the other end of the coil, and means for heating the cathode including a closed circuit in inductive relation to said first coil in which heating currents for the cathode may be induced, whereby a current may flow in one direction between the anode and cathode when the latter is heated, said device enabling a high frequency current to be built up and dissipated in the vessel without brushing or 90 corona effects. 95

9. A space-discharge device comprising elements within an evacuated vessel and means for impressing alternating energy thereon, the elements within the vessel including means for producing currents of extremely high potential from said alternating energy means and for rectifying said currents. 100

10. A space discharge device comprising an evacuated vessel having means therein for building up and rectifying currents of extremely high potential, said means including a cathode adapted to be heated by the passage of induced currents therethrough, and a coil having one end connected with the 110 cathode, and a single coil outside the vessel for inducing currents to be rectified in the coil and for inducing heating currents in the cathode. 115

In testimony whereof, I have hereunto 115 subscribed my name this 7th day of December 1922.

FREDERICK S. McCULLOUGH.
